UNITED STATES PATENT OFFICE.

SAMUEL W. CARROLL, OF CINCINNATI, OHIO.

COVER PLATE.

Application filed March 23, 1925. Serial No. 17,760.

To all whom it may concern:

Be it known that I, SAMUEL W. CARROLL, a citizen of the United States, residing at Cincinnati, in the county of Hamilton and 5 State of Ohio, have invented new and useful Improvements in Cover Plates, of which the following is a specification.

In winter weather cold outside air enters a room between the sides of a building 10 and the window casing and this air freely flows through the open face of the housing for the grooved wheels over which the weighted sash supporting cords are trained. To overcome the inconvenience and dangerous drafts thus created, is to be considered the object of this invention.

Specifically the improvement resides in a novel construction of cap member which is arranged over the outer face of the pulley 20 housing, provided with an opening through which the sash cord passes and held in proper position by the contact of said sash cord thereon.

Further the improvement comprises a flat 25 plate having an approximately central outbulged portion to receive therein the projecting portion of a sash cord pulley and having an opening through which the cord passes, the cord contacting with the plate, holding the same in position while the said 30 plate has an inner face of felt or like air excluding material to prevent the passage of air drafts therethrough.

In the drawings:

35 Figure 1 is a detail sectional view through a portion of a window casing and a sash cord pulley housing, illustrating the application of the improvement thereon, the latter being also in section.

40 Figure 2 is a face view of the construction disclosed in Figure 1.

Figure 3 is a perspective view of the improvement.

45 My improvement may be made of any desired material and has its body portion 1 in the nature of a comparatively thin substantially rectangular plate. The plate is approximately centrally bulged outwardly from its inner face to provide the same with 50 a housing or compartment 2 that is de-

signed to receive therein the outwardly projecting portion of a pulley 3 for a sash cord 4. The pulley 3 has its shaft journaled in the sides of the usual housing 5, and the said housing is secured on the sash by screws 55 in the usual manner. The plate 1, approximately in a line with the center of the outbulged portion 2 thereof, is formed with a lateral slot 6 that also extends through one side and enters the top of the outbulged portion 2. The slot 6 communicates with a slot 7 arranged centrally in the outbulged portion 2. Thus the improvement is provided with a substantially T-shaped slot, the lateral passage 6 of which is designed 60 to have the sash cord 4 first passed therethrough, when the cord is slackened, and after the sash cord is received in the longitudinal branch 7 of the said T-shaped slot the improvement may be arranged to cover 65 the pulley housing as illustrated in Figures 1 and 2 of the drawings. The sash cord bears against the outer and lower faces of the plate 1 and holds the device properly positioned. 70

On its inner face the improvement is provided with a facing of felt or like material, the same being indicated by the numeral 8 and being cut, as at 9, laterally in a plane with the center of the lateral 75 passage 6 of the T-shaped slot. Thus this passage is closed, as is also the open side of the bulged portion 2 of the improvement, so that little, if any air can enter through the well or pocket in the window casing 80 through the housing 5.

The simplicity of my improvement and the advantages thereof will be perfectly apparent from the foregoing description 85 when read on the drawings, by those skilled in the art to which such inventions relate.

What I claim is:

A cover plate for sash cord pulleys, comprising a flat member having a central outwardly bulged portion, said member designed to rest upon the side of a window casing and the bulged portion thereof designed to receive the sash cord pulley therein, a compressible strip on the inner face of the said member also arranged in the bulged 95 100

portion thereof, said member having a transverse slot communicating with its bulged portion and its bulged portion having an opening extending downwardly from the slot, and through which opening the sash cord passes, the compressible member being slitted, and having an opening align-

ing with the opening in the bulged portion and said member being held in sustained position by contacting engagement with the 10 sash cord therewith.

In testimony whereof I affix my signature.

SAMUEL W. CARROLL.
